United States Patent Office

Des. 181,360
Patented Nov. 5, 1957

181,360

TOILET TISSUE DISPENSER OR SIMILAR ARTICLE

Bernard Joseph, North Las Vegas, Nev.

Application March 11, 1957, Serial No. 45,175

Term of patent 14 years

(Cl. D4—3)

FIG. 1

FIG. 2

FIG. 3

Fig. 1 is a perspective view of a toilet tissue dispenser, showing my new design.

Fig. 2 is a top plan view thereof.

Fig. 3 is a bottom plan view thereof.

The opposite side of the dispenser is substantially the same in appearance as the side seen in Fig. 1.

I claim:

The ornamental design for a toilet tissue dispenser or similar article, as shown and described.
